UNITED STATES PATENT OFFICE.

ALFRED P. MORGAN, OF MONTCLAIR, NEW JERSEY.

DESIGN FOR AN INSTRUMENT MOUNT FOR RADIOPANELS.

60,362.

Specification for Design.

Patented Feb. 7, 1922.

Application filed July 27, 1921. Serial No. 488,025. Term of patent 14 years.

To all whom it may concern:

Be it known that I, ALFRED P. MORGAN, a citizen of the United States, residing in the town of Montclair, county of Essex, and State of New Jersey, have invented a new, original, and ornamental Design for an Instrument Mount for Radiopanels, of which the following is a specification, reference being had to the accompanying drawings, forming a part thereof, in which—

Figure 1 is a perspective view in elevation

of an instrument-mount embodying my design, and Figure 2 is a perspective plan view thereof, the dotted lines in these figures indicating openings for screws or the like means of attachment of the mount to a vertical or horizontal wall of a radio panel.

I claim:

The ornamental design for an instrument-mount for radiopanels as shown.

ALFRED P. MORGAN,
